UNITED STATES PATENT OFFICE.

JOSEPH E. JOHNSON, OF PARIS, TENNESSEE.

RAILWAY-VELOCIPED.

SPECIFICATION forming part of Letters Patent No. 660,298, dated October 23, 1900.

Application filed January 24, 1900. Serial No. 2,659. (No model.)

To all whom it may concern:

Be it known that I, JOSEPH E. JOHNSON, a citizen of the United States, residing at Paris, in the county of Henry and State of Tennessee, have invented a new and useful Railway-Velocipede, of which the following is a specification.

My invention relates to improvements in railway-velocipedes; and the primary object 10 that I have in view is to provide means adapted to be applied to and used in connection with an ordinary bicycle of the safety pattern for the purpose of converting such bicycle into a velocipede adapted to run with accuracy upon the rails of an ordinary track.

A further object is to provide a construction by which the velocipede is caused when in use to be retained on the track-rails and to pass safely over switches and crossings 20 against any tendency to derailment.

A further object is to provide an attachment of improved construction by which the wheels thereof may be adjusted to tracks which vary in gage and also are adapted to 25 bicycle-frames of different heights.

With these ends in view the invention consists in the novel combination of devices and in the construction and arrangement of parts, which will be hereinafter fully described and 30 claimed.

To enable others to understand the invention, I have illustrated a preferred embodiment thereof in the accompanying drawings, the latter forming a part of this specification, 35 and in which—

Figure 1 is a perspective view illustrating my attachment applied to an ordinary safety-bicycle and adapting the same for use as a velocipede for an ordinary railway-track. 40 Fig. 2 is a plan view of the complete railway-velocipede shown by Fig. 1. Fig. 3 is a rear elevation of the velocipede. Fig. 4 is an enlarged detail sectional view of the fitting or coupling which joins the series of bars and 45 is equipped with means for supporting the guide-wheel of the attachment. Fig. 5 is a detail sectional view of the clip, which is slidably adjustable in each of the bars forming the attachment. Fig. 6 is a vertical sectional 50 view through a part of the bicycle-frame, illustrating a hanger and a wheel supported thereby.

The same numerals of reference are used to indicate like and corresponding parts in each of the several figures of the drawings. 55

In carrying my invention into practice I employ two pairs of rods which converge to a common fitting or coupling, the rods of one pair being fastened to a front fork of a bicycle and the rods of the other pair being provided with means for attachment to the rear fork of a bicycle. The pair of rods for attachment to the front bicycle-fork are indicated by the numerals 10 and 11, while the other pair of rods for attachment to the rear 60 bicycle-fork are indicated by 12 and 13. The rods are preferably tubular, and, as before indicated, they converge from their points of attachment to the bicycle-frame to the common fitting or coupling 14, one type of which 65 is shown more clearly by Figs. 2 and 4 of the drawings. It is to be observed that the rods forming each pair converge toward each other and that the two pairs of rods converge laterally toward each other, whereby the divergent ends of the rods are capable of attachment at different points on the forks of the 70 bicycle-frame, so as to thoroughly brace and steady the latter.

The fitting 14 is shown by Fig. 4 as consisting of a plate having a series of arms 15 and a spindle 17, the arms of said fitting adapted to individually be received within the outer ends of the converging tubular rods, suitable clamping-screws 16 being 85 mounted in the ends of the tubular rods, so as to bind against the arms of the fitting for the purpose of holding the outer ends of the tubular rods practically at a common point. The spindle 17 extends from the plate of the 90 fitting or coupling, on the opposite side thereof from the series of arms, and on this spindle is revolvably mounted the guide-wheel 18, which is adapted to one of the rails of the track. I prefer to equip this guide-wheel 18 95 with ball-bearings 19 and with an internal flange 20, the latter adapted to ride against the inner edge of a track-rail. It is also my practice to employ a cushion-tread 21 on the periphery of the wheel, said tread being in 100 the form of an annular band of rubber, leather, or other suitable material adapted to minimize the vibration and noise due to the travel of the wheel on the track-rail.

The tubular rods of the attachment are provided at their inner ends with clips 23, one of which is shown more clearly by Fig. 5. This clip has a shank, which is insertible in the inner end of the tubular rod, so as to be held therein by a binding-screw 24. The projecting end of the clip is formed with an elastic or divided eye 25, which may be fitted around a member of the bicycle-fork, and this eye-formed end of the clip has a plate 26, which overlaps the shank 23, whereby a binding screw or bolt 27 may be passed through the shank and the plate for the purpose of firmly holding the parts together and making the eye fast with the fork. My attachment also contemplates the employment of a steady-ing-wheel, which is arranged between and in alinement with the front and rear wheels of a bicycle, and this steady-ing-wheel is mounted in an extensible or adjustable hanger 28, which is clamped firmly to the horizontal and inclined reach-bars of the bicycle-frame. (See Figs. 1 and 6.) This hanger 28 is shown as embodied in a metallic bar, doubled or bent upon itself so as to fit over the reach-bars in a manner to straddle the upper reach-bar and to laterally embrace the lower inclined reach-bar. To minimize the abrasion on the enamel or finish of the bicycle-frame, I prefer to interpose pads 29 of any suitable material between the hanger and the reach-bars, and this hanger is clamped firmly in place by drawing its branches together through the medium of the bolts 30. The doubled hanger has its ends below the inclined reach-bar bent to form the diverging legs 31, against which legs are applied the extension-straps 32, which are fastened adjustably to the hanger, so as to raise or lower the steady-ing-wheel. These extension-straps are provided with longitudinal slots 33, and they are applied laterally against the hanger-legs, so as to receive the clamping-bolts 34, whereby the straps may be raised or lowered on and clamped firmly to the hanger. An axle 35 is supported in any suitable way in the lower ends of the extension-straps, and on this axle is revolvably fitted the steady-ing-wheel 36, the same being arranged between the straps, as shown more clearly by Fig. 6.

The steady-ing-wheel is provided at its inner edge with an annular radial flange 37, and this wheel may or may not be furthermore provided with a cushion-tread.

In the adaptation of my invention shown by Figs. 1 to 3, inclusive I have illustrated a bicycle of the ordinary "safety" pattern and which is indicated in its entirety by the numeral 38, said safety-bicycle being of the usual chainless variety and equipped with inflatable tires and other accessories. I do not desire, however, to confine myself to any particular style of bicycle, because the improvements of my invention are applicable to different kinds of bicycles, as will be obvious to those skilled in the art.

In applying my improvements to a bicycle

the clips 23 of the several rods are adjusted to the front and rear forks substantially as shown by Fig. 1, and the clamping-screws 27 are tightened to make the clips and the rods fast with the frame. The hanger 28 is also applied to the upper and lower reach-bars, so as to support the steady-ing-wheel 36 in a position between and in alinement with the front and rear wheels of the bicycle. If desired, the tubular rods may be adjusted on the arms of the fitting and the shanks of the clips to place the guide-wheel at a proper distance from the steady-ing-wheel, and thereby enable the several wheels of the velocipede to travel on the rails of an ordinary track. This adjustment of the parts provides for the velocipede traveling on tracks which may vary in gage. The adjustment of the extension-straps on the legs of the hanger enables the steady-ing-wheel to be raised or lowered, so that the bicycle-wheels may properly ride on the track-rail. It will be noted that the guide-wheel and the steady-ing-wheel are provided on their opposing or contiguous sides with the annular flanges, and this construction is important, because the velocipede is adapted to travel over crossings and through switches of a railway-track with safety, thus minimizing any tendency to derailment of the velocipede. The machine may be propelled by foot-power in the ordinary way, and the divergence of the two pairs of rods toward the bicycle-frame enables the rider to propel the machine without hindrance from the attachment. The tubular rods and the hanger may be readily disconnected, so that the bicycle can be used in the ordinary way.

My attachment is simple in construction, efficient and durable in service, and is comparatively cheap of manufacture. The use of the attachment converts a bicycle into a velocipede adapted to maintain itself on a track and to travel with safety over crossings and through switches.

Changes within the scope of the appended claims may be made in the form and proportion of some of the parts, while their essential features are retained and the spirit of the invention is embodied. Hence I do not desire to be limited to the precise form of all the parts as shown, reserving the right to vary therefrom.

Having thus described the invention, what I claim is—

1. An attachment for railway-velocipedes comprising a fitting or coupling, two pairs of rods converging toward said coupling and having means for attachment to the front and rear forks of a bicycle-frame, a wheel mounted on said fitting or coupling, and a wheeled hanger attachable to the bicycle-frame between the attachment of the respective pairs of rods, substantially as described.

2. An attachment for railway-velocipedes comprising two pairs of rods converging toward each other and each having means for attachment to the front and rear forks of a

bicycle, a fitting to which said rods are individually secured, a wheel revoluble on said fitting, and a hanger also adapted for attachment to a bicycle-frame and carrying a steady-
5 ing-wheel, substantially as described.

3. An attachment for railway-velocipedes comprising two pairs of tubular converging rods provided with means for fastening the same to the front and rear forks, respectively, 10 of a bicycle-frame, a fitting adjustably fastened to said rods at one end thereof, attaching-clips connected adjustably to the rods at the other ends thereof, and a wheeled hanger attachable to the bicycle-frame between the 15 attachment of the respective pairs of rods, substantially as described.

4. An attachment for railway-velocipedes, comprising two pairs of tubular rods, a series of clips each clamped to one of said rods and 20 having an eye adapted to be clamped to a bicycle-frame, said series of eye-clips arranged to fasten the respective pairs of rods to the front and rear forks of said bicycle-frame, and a wheel revolvably supported at the outer ends 25 of said rod, substantially as described.

5. An attachment for railway-velocipedes comprising a vertical hanger having means for engagement with the reach-bars of a bicycle-frame between the wheels thereof, a 30 steadyng-wheel, and means for adjustably supporting said wheel on said hanger, substantially as described.

6. An attachment for railway-velocipedes comprising a hanger, extension - straps

clamped to the hanger and adjustable length- 35 wise thereon, an axle mounted in the extension-straps, and a steadyng-wheel on said axle, substantially as described.

7. In a railway-velocipede, the combination with a bicycle, of a series of rods clamped to 40 the front and rear forks of said bicycle and converging toward each other, a spindle supported by said rods at their convergent ends, a guide-wheel revoluble on said spindle, a hanger clamped on the frame of said bicycle 45 between the front and rear wheels thereof, and a steadyng - wheel supported by the hanger between the front and rear bicycle-wheels, substantially as described.

8. In a railway-velocipede, the combination 50 with a bicycle, of pairs of converging bars clamped to the front and rear bicycle-forks and converging at their outer ends, a guide-wheel supported at said outer ends of the bars and provided on its inner side with a 55 rail-flange, a hanger clamped to the reach-bars of the bicycle-frame, and a steadyng-wheel journaled in the hanger between the bicycle-wheels and likewise provided on its inner side with a rail-flange, substantially as 60 described.

In testimony that I claim the foregoing as my own I have hereto affixed my signature in the presence of two witnesses.

JOSEPH E. JOHNSON.
